(57) **CLAIM**

The ornamental design for a front face of a vehicle wheel, as shown and described.

DESCRIPTION

FIG. 1 is a front view of a front face of a vehicle wheel showing my new design; and,

FIG. 2 is a top and left side perspective view of the wheel shown in FIG. 1.

The broken line showing of the rear of the wheel is included for the purpose of illustrating environment and forms no part of the claimed design.
